[**] Term: 14 Years

Primary Examiner—Susan J. Lucas

Attorney, Agent, or Firm—James E. Bradley

[21] Appl. No.: 747,207

CLAIM

[22] Filed: Aug. 16, 1991

The ornamental design for an extra wide angle fresnel
lens array for infrared motion detector, as shown and
described.

[52] U.S. Cl. D26/122

DESCRIPTION

[58] Field of Search D26/120, 122; D10/114,
D10/121; 362/326, 329-340; 359/742, 743

The single FIGURE is a front elevational view of an
extra wide angle fresnel lens array for infrared motion
detector showing my new design, the lens array being a
flat, rectangular, thin sheet having a front surface with
grooves thereon and a plain, smooth rear surface with
no ornamentation.
